[57] **CLAIM**

The ornamental design for a game projectile launcher, as shown.

DESCRIPTION

FIG. 1 is a perspective view of a game projectile launcher showing my new design;

FIG. 2 is a top plan view of the launcher;

FIG. 3 is a sectional view taken along the line 3—3 in FIG. 2;

FIG. 4 is an end elevational view of the launcher;

FIG. 5 is an end elevational view of the launcher opposite from the end represented in FIG. 4.
